(57) **CLAIM**

The ornamental design for the eyewear frame heater, as shown and described.

DESCRIPTION

FIG. 1 is a top front right side isometric view of an eyewear frame heater showing my new design according to an embodiment;

FIG. 2 is a top front left side isometric view of the eyewear frame heater of FIG. 1;

FIG. 3 is a front end view of the eyewear frame heater of FIG. 1;

FIG. 4 is a rear end view of the eyewear frame heater of FIG. 1;

FIG. 5 is a right side view of the eyewear frame heater of FIG. 1;

FIG. 6 is a left side view of the eyewear frame heater of FIG. 1;

FIG. 7 is a top plan view of the eyewear frame heater of FIG. 1; and,

FIG. 8 is a bottom plan view of the eyewear frame heater of FIG. 1.

The shade lines in the Figures show surface contour and not surface ornamentation.
